RADIATOR ENCLOSURE

John P. Mascolo, Brooklyn, N. Y.

Application August 13, 1953, Serial No. 374,065

1 Claim. (Cl. 237—78)

This invention relates to a radiator enclosure and more specifically provides for an enclosure that is easily assembled, and it provides a wafer pan which is positioned over the conventional radiator and presents a pleasing appearance as a cover and enclosure for a conventional radiator.

An object of this invention is to provide a radiator enclosure which has no welded parts and may be easily assembled and disassembled.

An important object of this invention is to provide a radiator enclosure which has a removable top and a removable water pan positioned over the conventional radiator.

Another object of this invention is to provide a radiator enclosure which has removable members which act as a fastening means for the various panels of the enclosure and also acts as a support for the water pan.

A further object of this invention is to provide a radiator enclosure that may be folded for shipping and one in which the production cost is at a minimum and one in which a pleasing appearance for a conventional radiator is obtained.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of the radiator enclosure of this invention showing the device in installed position in a room;

Figure 2 is a top plan view of the structure of Figure 1 with the top removed showing the details of the front, end, and back members;

Figure 3 is a longitudinal, vertical section taken substantially along section line 3—3 of Figure 1 showing details of the top mounting and the water pan support;

Figure 4 is a fragmental, longitudinal, vertical section taken substantially along section line 4—4 of Figure 2 showing details of the back member and the ends of the hinge pins and their attachment to the end panels;

Figure 5 is a perspective rear-end view of the front panel showing the inturned edges and the hinge barrels on said edges;

Figure 6 is a perspective, detailed view of the end panels showing the details of the inturned edges, the hinge barrels, and the apertures for receiving the fastening means for the back member and the hooked end portion of the hinge pins; and

Figure 7 is a perspective, detailed view showing one of the right angular hinge pins having a hooked end portion.

Referring now more specifically to Figures 1 to 3 in the drawings, it will be seen that the numeral 10 generally designates the radiator enclosure of this invention positioned over a radiator 12 and setting on a floor 14.

As clearly seen in the drawings, the radiator enclosure

10 is composed of a front panel 16 having a reticulated center portion 18, a left-hand end panel 20 and a right-hand end panel 22, a back angle member 24 which connects the end panels 20, 22 and a top member 26 which rests on the upper edges of the panels 16, 20, and 22 and the back angle member 24. As best seen in Figure 5, the front panel member 16 has inturned edges 28 along each side and the edges 28 are provided with a hinge barrel 30 adjacent the mid-portion of each edge 28. 5 Each of the end panels 20 and 22 is composed of a substantially channel-shaped member with the legs thereof being turned inwardly towards each other forming edges 32 and 34. On the forward edge 32 is provided a pair of hinge barrels 36 which are similar to the hinge barrel 30 and spaced apart a distance which is equal to the length of the hinge barrel 30. The rear edge of the end panels 20 and 22 are provided with upper and lower apertures 38 and 40 which are adjacent the edge of the panel members 20 and 22. The back angle member 24 15 which connects the rear edges 34 of the end members 20 and 22 together has inturned end portions 42 having apertures therein which meet with apertures 38 and secured thereto by suitable fastening means such as bolts 44 as clearly seen in Figure 4. As best seen in Figure 2, the front panel 16 and the end panels 20 and 22 are connected together by a hinge pin 46 of right angular configuration and made of any suitable wire member. The hinge pin 46 has a vertical leg which extends into the hinge barrels 30 and 36 when they are in assembled 20 position and a horizontal leg which terminates in a hooked end portion 48 for a purpose described herein-after.

In assembling the radiator enclosure the front panel 16 and the end panels 20 and 22 are connected together by placing the hinge barrels 36 in alignment with hinge barrels 30 and inserting the hinge pin 46 through the barrels as best shown in Figure 2. The back angle bar member 24 is placed across the rear portion between the end members 22 and 20 and bolts 44 are inserted through the apertures 38 in the rear edges of the end panels 20 and 22 and through the downturned ends 42 of the member 24 and the rectangular member now is in assembled position. The hooked end portions 48 of the hinge pins 46 are positioned in such a manner that they extend 25 across from the hinge barrels 30 and 36 to the rear edge portion 34 of the end panels 20 and 22, and these end portions 48 of the hinge pins 46 engage the lower apertures 40 in the rear edges 34 of the end panels 22 and 20 in a manner as best shown in Figure 4. A tray-type 30 water pan 50 is supported in the horizontal portion of the hinge pins 46 and it will be readily seen that the tray is rigidly supported by the action of the hooked end members 48 and the upper edges of the hinge barrels 36 which act against the horizontal portion of the hinge pins. The water pan 50 may be removed and refilled 35 with water in an obvious manner and the tray is of such a width that it fits between the front edges 32 and the rear edges 34 of the end panels 20 and 22. The top 26 has downturned edges 52 around the periphery thereof and the edges 52 engage the front panel, end panels, and back member to locate the top 26 and close the top of the rectangular member formed by the front side and back member.

By removing the top, the water tray, and the back 40 member 24, and disengaging the hinge pins the device may be completely disassembled for easier shipping or storing or the device may be folded by merely removing the top, tray, and the back member and pivoting the end panels about the hinge pins for easier insertion into a shipping carton. The device may be made of any suitable sheet material such as aluminum, thin gauge steel,

or other sheet metal and may be painted any desired color or decorated in any desired manner.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claim.

What is claimed as new is as follows:

A radiofor enclosure comprising a front panel, two end panels detachably secured to said front panel by hinge means including barrels and removable hinge pins 15 which coact with the barrels, a back member connecting said end members together with a removable rectangular top resting on the top edges of said panels and back

member, said removable hinge pins between the front panel and the end panels being provided with offset horizontal portions, a water pan supported on said portions and adapted to be heated by a radiator, each of said horizontal portions terminating in a free hook end portion, said hook end portion of each hinge pin engaging an aperture in the end panels thereby retaining the hinge pins in the barrels and retaining the barrels in alignment and supporting the water pan in horizontal position.
